Utility U.S. Appl. No. 13/408,962, filed Feb. 29, 2012, entitled Hanging Organizer, Matthew J. Carr et al.

Primary Examiner — Jennifer Rivard

(74) Attorney, Agent, or Firm — Simpson & Simpson, PLLC

(57) **CLAIM**

The ornamental design for a corset-shaped organizer, as shown and described.

DESCRIPTION

FIG. 1 is a front perspective view of the present invention corset-shaped organizer;

FIG. 2 is a rear perspective view of the invention;

FIG. 3 is a front elevational view of the invention;

FIG. 4 is a rear elevational view of the invention;

FIG. 5 is a left side elevational view of the invention;

FIG. 6 is a right side elevational view of the invention;

FIG. 7 is a top plan view of the invention; and,

FIG. 8 is a bottom plan view of the invention.

The broken lines in the drawings depict environmental subject matter only and form no part of the claimed design.

1 Claim, 6 Drawing Sheets
